B. S. NELLANS,
RESILIENT WHEEL,
APPLICATION FILED DEC. 11, 1915.

1,213,936.

Patented Jan. 30, 1917.

UNITED STATES PATENT OFFICE.

BRODIE S. NELLANS, OF ELBING, KANSAS.

RESILIENT WHEEL.

1,213,936.

Specification of Letters Patent. Patented Jan. 30, 1917.

Application filed December 11, 1915. Serial No. 66,303.

To all whom it may concern:

Be it known that I, BRODIE S. NELLANS, a citizen of the United States, residing at Elbing, in the county of Butler and State 5 of Kansas, have invented certain new and useful Improvements in Resilient Wheels; and I do hereby declare the following to be a full, clear, and exact description of the invention, such as will enable others skilled 10 in the art to which it appertains to make and use the same.

My invention relates to an improved vehicle wheel and more particularly pertains to that type of wheel which is used in connection with automobiles and one of such 15 construction as to dispense with the use of pneumatic tires.

The primary object of my invention resides in the provision of means, whereby 20 the weight or stress is distributed longitudinally of the periphery of the wheel.

Another object of my invention is to overcome the resistance encountered by the wheel on uneven surfaces of the road and by obstacles 25 thereon, such as rocks, etc.

A further object is to provide for the securing of the wheel spokes to the spring members and means for connecting the 30 spring members to the felly.

The invention consists of the novel features, details of construction and combination of parts, which hereinafter will be more particularly set forth, illustrated in the accompanying drawings, and pointed 35 out in the appended claims.

Referring to the drawings, forming a part of the application.

Figure 1 is a front elevational view of my improved wheel with portions broken away, 40 and, Fig. 2 is a bottom plan view on line 2-2 of Fig. 1, showing the spring members, with the tire supporting bolts in section. Fig. 3 is a vertical transverse sectional view on line 3-3 of Fig. 1 looking in the direction of the arrow.

Corresponding and like parts are referred to in the following description, and indicated in all of the views of the drawings, by the same reference numerals.

The wheel comprises a hub 1, having radiating therefrom, a plurality of spokes 2, which are preferably constructed of wire, though it is to be understood that the well known type of wooden spokes may be likewise employed. The spokes 2 may be secured to the hub in any suitable manner and

have their opposite ends screw threaded at 3. The cushioning means for said wheel comprises the spring unit members 4 and 5, and the connecting strap member 6, the spring 60 unit members 4 and 5 being secured to the spokes 2, in the following manner: Each spring unit consists of a number of strap members, preferably three, which are superposed with two of them engaging each other, 65 while the other one is spaced therefrom by blocks 7, which latter receives the threaded end 3 of the spokes 2, the outer ends of the spokes terminating flush with the outer face of the strap member 6, and if desired, said 70 ends may be upset or riveted. Spring unit members 4 and 5, are held in spaced relation by the connecting strap members 6, which is arranged with a continuation of integral triangular formations 8 or it is substantially zig-zag in construction and the 75 spokes 2 pass through the strap member 6, at the central portions of the apex of each of the triangular formations 8.

The members 4 and 5 are held in fixed position upon the spokes 2 by means of nuts or threaded blocks 9 which engage the threaded ends 3 of the spokes 2 and bear upon the respective inner surfaces of the innermost spring unit members 4 and 5 when 80 screwed down on said members and, directs outward pressure thereon and gives tension thereto. Midway between the points of attachment of the spokes with the respective spring unit members 4 and 5, and interposed between the respective inner and outer 85 spring units thereof, are the blocks 10, which have threaded apertures adapted for the reception of the threaded ends 11, of the felly supporting bolts 12, and the nuts 13 90 and 14 bind respectively against the outer face of the outer spring member and the inner face of the inner spring member. The opposite ends of the supporting bolts 12, are formed into yokes 15 which are attached to 95 the felly by means of rivets 16, or the like.

The felly proper, comprises a plurality of convoluted sheets of spring metal 19, and to certain of the inner convex portions 20 of said felly are secured the yokes 15, by 100 means of the rivets 16. A rubber tire 22 is molded on the felly and serves to further cushion the wheel preventing the contact of the felly with the road surface. It will thus be seen that the weight on the wheel will be 105 jointly supported by the springs of the spring unit members 4 and 5 and the felly 110

in turn through the yokes 15 and bolts 12, and any resistance encountered by the felly will be dissimulated through the convolutions 19 thereof. Likewise the spring unit 5 members 4 and 5, connected at their central parts to the bolts 12, will give, under pressure, and serve to further cushion the wheel.

It is obvious that in a wheel of this type, the weight of the machine carried thereby 10 will be cushioned first by the spring units 4 and 5 at their point of contact with the spokes, secondly, through the unit members with the bolts 12 at their medial portions, and thirdly by the contact of the yokes 15, 15 with the convolutions 19 of the felly, and lastly the natural cushioning of the felly and the rubber tire 22.

While I have shown and described my invention in this particular form, it is to 20 be understood that changes, variations, and modifications can be resorted to that may come within the scope of the claims hereto appended.

Having described my invention, what I 25 claim as new and desire to secure by Letters-Patent, is:—

1. A resilient wheel, comprising a hub, 30 spokes carried by said hub and having their ends in alternate staggered relation to provide spoke series, spring members secured to the spokes of each series, a spring felly for said wheel, means connecting the springs of the spoke series to said spring felly, and a zigzag reinforcing band secured 35 consecutively to the ends of the alternating spokes for maintaining the spoke series and their spring members in lateral spaced relation.

2. A resilient wheel, comprising a hub 40 having spokes provided with screw threaded ends disposed in alternate staggered relation to each other to provide spoke series, a plurality of superposed spring bands se-

cured upon the threaded ends of each of the spoke series and lying in spaced parallelism 45 to each other, an angular reinforcing band having angular sectors secured to the extremities of said spokes for connecting the alternate spokes of one series to the alternate spokes of the other series for maintaining 50 said spokes and said spring bands in operative position, a felly for said wheel consisting of a plurality of superposed convolute spring members provided with a resilient tread member, and bolts for connecting 55 said felly to the respective spring bands of said spoke series.

3. A resilient wheel, comprising a hub having spokes provided with screw threaded ends disposed in alternate staggered relation 60 to each other to provide spoke series, a plurality of superposed spring bands secured upon the threaded ends of each of the spoke series and lying in spaced parallelism to each other, an angular reinforcing band 65 having angular sectors secured to the extremities of said spokes for connecting the alternate spokes of one series to the alternate spokes of the other series for maintaining said spokes and said spring bands in operative position, a felly for said wheel consisting of a plurality of superposed convolute spring members provided with a resilient tread member, and bolts connecting each 70 alternate convolute of said spring felly to 75 the respective spring bands of said spoke series at a point midway between the ends of the spokes of said series.

In testimony whereof I have signed my name to this specification in the presence of 80 two subscribing witnesses.

BRODIE S. NELLANS.
